UNITED STATES PATENT OFFICE

166,399

EARMUFF

John Lattuca, Brooklyn, N. Y.

Application March 22, 1951, Serial No. 14,587

Term of patent 3½ years

(Cl. D3—2)

To all whom it may concern:

Be it known that I, John Lattuca, a citizen of the United States, residing at Brooklyn, New York, in the county of Kings and State of New York, have invented a new, original, and ornamental Design for an Earmuff, of which the following is a specification, reference being had to the accompanying drawing, forming part thereof.

In the drawing:

Fig. 1 is a front elevational view of an earmuff, showing my new design;

Fig. 2 is an end elevational view of the same, the other end being identical to this figure;

Fig. 3 is a view similar to Fig. 2, but with the propeller, which is attached to the clown's nose, removed so that the design may be easily seen; and

Fig. 4 is an elevational view of the inner side thereof looking in the direction of the arrows 4—4 of Fig. 1.

I claim:

The ornamental design for an earmuff, as shown and described.

JOHN LATTUCA.
